(57) **CLAIM**

The ornamental design for an electrical connector as shown and described.

DESCRIPTION

FIG. 1 is a front, top and left-side perspective view of an electrical connector showing my new design;

FIG. 2 is a rear, top and right-side perspective view thereof; FIG. 3 is a front, bottom and right-side perspective view thereof;

FIG. 4 is a rear, top and left-side perspective view thereof;

FIG. 5 is a front elevational view thereof;

FIG. 6 is a rear elevational view thereof;

FIG. 7 is a left-side elevational view thereof;

FIG. 8 is a right-side elevational view thereof;

FIG. 9 is a top plan view thereof;

FIG. 10 is a bottom plan view thereof;

FIG. 11 is an enlarged view of the area 11 indicated by the double dot-dash broken lines in FIG. 1;

FIG. 12 is an enlarged view of the area 12 indicated by the double dot-dash broken lines in FIG. 1;

FIG. 13 is an enlarged view of the area 13 indicated by the double dot-dash broken lines in FIG. 2;

FIG. 14 is an enlarged view of the area 14 indicated by the double dot-dash broken lines in FIG. 2;

FIG. 15 is an enlarged view of the area 15 indicated by the double dot-dash broken lines in FIG. 3;

FIG. 16 is an enlarged view of the area 16 indicated by the double dot-dash broken lines in FIG. 3;

FIG. 17 is an enlarged view of the area 17 indicated by the double dot-dash broken lines in FIG. 4;

FIG. 18 is an enlarged view of the area 18 indicated by the double dot-dash broken lines in FIG. 4;

FIG. 19 is an enlarged view of the area 19 indicated by the double dot-dash broken lines in FIG. 5;

FIG. 20 is an enlarged view of the area 20 indicated by the double dot-dash broken lines in FIG. 5;

FIG. 21 is an enlarged view of the area 21 indicated by the double dot-dash broken lines in FIG. 9; and,

FIG. 22 is an enlarged view of the area 22 indicated by the double dot-dash broken lines in FIG. 9.

The evenly spaced broken lines depict portions of the electrical connector that form no part of the claimed design. The single dot-dash broken lines define the boundaries of the claimed design and form no part of the claimed design. The areas indicated by the double dot-dash broken lines shown in FIG. 1 through FIG. 5, FIG. 9 and in FIG. 11 through FIG. 22 illustrate the boundaries of enlarged areas of the design. The “11”, “12”, “13”, “14”, “15”, “16”, “17”, “18”, “19”, “20”, “21” and “22” indicia and splined curve indicated by the double dot-dash broken lines shown in FIG. 1 through

(Continued)

FIG. 5 and in FIG. 9 identify the enlarged areas. The double dot-dash broken lines form no part of the claimed design.
